CABLE CODE PRINTER

Application filed December 24, 1931. Serial No. 583,003.

The present invention relates to improvements in cable code printers of the type disclosed in an application of A. F. Connery and M. H. Woodward, filed December 15, 1930, Serial Number 502,404. The invention provides simplified means for the printing of short figures or figure abbreviations; means for preventing the printer from operating when no traffic is being transmitted and only a signal for maintaining synchronism is being received; and simplified intermediate circuits using polarized relays. In describing these features a brief description of the entire apparatus is given, in order that the relation of the improvements to the whole may be made clear. The scope of the improvements is clearly defined in the claims.

One of the objects of the invention is to provide means for making the printer non-responsive to received signals when no traffic is being handled and the only signals received are those for maintaining synchronism. Intimately connected with this feature is the provision for automatically restoring the printer to operable condition when a special signal is received to indicate resumption of traffic.

Another object of the present invention is to provide simplified means for printing figures when the short figure signals of the cable code are received while the printer is in the upper case position.

A still further object is to provide a simple intermediate circuit for receiving signal impulses and relaying them to the other apparatus.

Further objects and the means for accomplishing them will be disclosed in the specification in conjunction with the drawings.

In the drawings:

Figure 1 shows the cable code and the corresponding five-unit printer code, together with the type bar selected by each combination of that printer code;

Figure 2 is a schematic drawing of the circuits employed to accomplish the various objects mentioned.

Each type bar of the five-unit code printer which is to be used in connection with this invention, is equipped with upper and lower

case characters either of which may be printed, depending upon the position of the printing platen. The normal position of the printing platen is the lower case.

A system of relays associated with the printer is arranged to energize a magnet in the printer which will shift the printing platen to the upper case position whenever a cable signal comprising five or more dots or dashes is received. When the printer is shifted to the upper case, it will remain in the shifted position until the "word space" signal is received which will simultaneously actuate the spacing mechanism and shift the printer into the lower case. In addition to this the printer is so arranged that it will unshift whenever a special unshift combination is transmitted. The figure shaft arrangement disclosed herein makes it possible to print directly from signals normally adapted to be transcribed from a siphon recorder tape. Line time is saved by the use of short figures and by the automatic figure shift and release mechanism. Sometimes, due to transmission or line failures, impulses may drop out, causing what are known as "double spaces". When signals are being copied by an operator from a siphon recorder tape, distorted signals of this type can be detected by the operator, but when a printer is used, a drop out will cause a wrong letter to be printed, which makes automatic reception undesirable for messages in code. This invention overcomes this difficulty by printing a special character whenever a double space is received, thus indicating that the message should be corrected.

Referring to Fig. 1, it will be noted that each letter of the cable code alphabet selects a different combination in the five-printer unit, but there is a conflict between certain cable code letters and figures; for example, the printer combinations for the letter J and the figure 1 are identical, but since the letter J has less than five dots and dashes, the printer platen will be in the lower case position and the letter J will be printed when a signal combination is received. The combination for figure 1 will cause the printer platen to shift to the upper case position

and the same type bar will then print figure "1". In the same manner the letter V and the figure 3 have the same printer combination, as have several other letters and figures.

5 Since the regular code combinations for the figures are made up of five units, it is customary when using a siphon recorded for reception, for the sending operator to abbreviate certain figures in order to save time. The following abbreviations for figures are generally used in commercial practice:

15 Figure 1 is set up as letter A;
 Figure 2 is set up as letter U;
 Figure 5 is set up as letter E;
 Figure 8 is set up as letter D;
 Figure 9 is set up as letter M;
 Figure 0 is set up as letter T;

20 In transmitting a group of figures it is customary to transmit the first figure of a group as a long figure, and to abbreviate the remainder of the figures. An arrangement has been provided in the present invention so that the abbreviated figures will be printed as figures rather than letters, provided that the first figure of a group is a long figure, which will serve to shift the printer to the upper case. This is accomplished by putting the proper figure on the same type bar with the letter corresponding to that figure, and arranging the circuits so that when the cable code combination for any long figure is received, the printer will shift to the upper case printing position and remain in the shifted position until either a word space or unshift signal is received. Meanwhile if a short figure signal is received, the printer will operate and print the corresponding figure. Means for accomplishing this shift and the printing of a figure when a short figure combination is received, will be described hereinafter in detail.

45 The actual operation of the printing circuits will now be explained in detail, reference being made to Figure 2. It should be understood that the transmission at the distant end of the cable must be automatic so that the signals are sent out at constant speed. The distributor at the receiving end of the cable is operated in synchronism with the received signals and operates the printing circuits.

55 Magnets 1-5, inclusive, represent the five selecting magnets of a printer. The start magnet and the figure shift magnet are shown by 6 and 7, respectively. All the relays in this drawing are of the neutral or non-polarized type, except intermediate relays 26 and 34, which are polarized. All relays are shown in their normal positions. In tracing the circuits reference will be made to the relay tongues resting on the marking and spacing contacts. It will be understood that the relay tongue moves to its marking position 60 when the relay is operated, and that when the

relay is de-energized, the tongue will move to its spacing position. Dot and dash receiving relays are shown, respectively, as 9 and 10, and it is to be understood that the dot or dash relays will be operated when the dots or dashes of the cable signal are received. The actual coupling of these dot and dash relays to the cable may be done in any suitable manner, and since it is well known in the art, and forms no part of this invention, there is no need to describe it here in detail. A developed view of the distributor is shown at 11 and the brushes 12 are assumed to be in synchronism and in suitable phase relation with the operation of the dot and dash relays 9 and 10. Methods of maintaining the distributor brushes in synchronism with the received signals are well known, and any suitable means may be employed with this invention.

70 The segments of the distributor are arranged in groups of three, every third segment being connected together, any suitable number of groups being arranged in the distributor face plate. The brush 12 as it rotates connects positive battery 40 to the segments. The segments of the respective groups are indicated in Fig. 2 of the drawings by the letters C, B and A. The arrangement is such that the brush passes over the three segments in the order C, B, A each time a dot, dash or zero signal is received. The transit time of the brush over the segments is about one-half the duration of each impulse, and the segmented ring is so oriented in relation to the incoming signals that the brush passes over the C, B and A group while the central portion of each impulse is being received.

75 As the brush passes over each C segment, positive battery is connected through the windings of relay 33 to ground, operating the relay and opening the locking circuit from battery 45, which releases any relay in the circuit that might have been locked due to a prior selection. When the brush passes over a B segment and the impulse then being received is a dot, the signal of which it forms part comprising less than five dots and dashes, positive battery 40 is connected over the contacts of relay 21 and contacts of relays 35 and 34 to the winding of the first selector magnet 1 and thence to ground. In other cases the impulses of a B segment serve to control the various relays in a printer selector system.

80 90 95 100 105 110 115 120 125 130 135 As the brush passes over an A segment the circuit is closed from positive battery through tongue A and contact of relay 35 to operate relay 13. It is to be noted that relay 13 operates only on a dot or dash, while relay 14 operates when a zero signal is received. After the operation of relay 15, which occurs when brush 12 leaves the A segment, relays 16, 17, 18, 19, and 20 operate and lock up progressively, (the number operating depending

on the number of dots and dashes in a character), as the brush passes over the segments indicated by the letter A.

Key 55 is provided in order to permit the de-energization of relay 21 by short circuiting its locking winding through a circuit from battery 56, tongue B of relay 21 and resistance 61 to ground. When relay 21 has thus been de-energized, it will operate again only when relay 20 is operated. Since relay 20 is the last one of the chain of relays 14-20, it will be operated only when a signal containing more than five dots and dashes is received. Consequently depression of key 55 and consequent de-energization of relay 21 breaks the circuit from the B segments to tongue C of relay 35 and thus removes battery from the circuits to the printer magnets and to filling in relays 27, 28, 29 and prevents their operation while synchronizing signals are being received, since the type of signal chosen to keep the distributors in synchronism during idle periods does not have sufficient dots or dashes to step up the counting relay bank to its limit. The magnets are restored to operative position when a signal containing more than five dots and/or dashes is received, for the counting bank then operates to the limit and battery 60 applied over the contacts of relay 20 operates relay 21 which then locks, the key having been released to break the short circuit around the locking winding.

Assume now that the signals corresponding to the letters AN are received, and that they are in proper phase relation with the distributor segments as shown by curve 41 at the top of Fig. 2. Before brush 12 reaches the first group of segments, the dot relay 9 will close its contacts and a circuit will be completed from positive battery thru the lower half of potentiometer 58, the middle winding of intermediate relay 26, the winding of intermediate relay 34, tongue and marking contact of the dot relay to negative plate of battery 42. A circuit is also set up from positive battery through the spacing contact of dash relay 10, the upper winding of relay 26, the lower portion of potentiometer 57 to positive battery. Also the biasing current through the lower winding of relay 26 is maintained at all times over a circuit from the positive plate of battery 42 through resistance 59 and lower winding of relay 26 to the negative pole of the same battery. When positive battery is flowing from the right to the left-hand terminals of any winding of relays 26 or 34, the tongue of that relay will tend to move to its marking contact. It will be seen that under the conditions just set forth, relay 26 will have its tongue lying on the marking contact while relay 34, due to the current flowing in the upper and lower windings, will also have its tongue lying on the marking contact.

When the tongue of relay 26 moves to its marking contact relay 35 will operate, and when tongue B of relay 35 leaves its spacing contact ground will be removed from the locking circuit of relays 13 and 15 and these relays will be de-energized. As tongue A of relay 13 leaves its contact it will cut off locking battery from all the relays of the counting bank 13-20, which may have been operated by a previous selection, and the tongues will fall back to the spacing position. As brush 12 passes over segment C relay 33 will operate, cutting off battery 45 and unlocking all the relays the locking windings of which are connected to its armature A. During the time that the brush is on the B segment a circuit will be completed from positive battery 40 through the tongue A of relay 21 and co-operating contact, tongue C of relay 35 and its marking contact, tongue of relay 34 and its marking contact, tongue B of relay 15 and its spacing contact, and selector magnet 1 of the printer to ground, causing selector magnet 1 to operate.

The brush now passes over the A segment which operates relay 13 over a circuit from positive battery 40 through brush 12, segment A, tongue B and spacing contact of relay 15, tongue A and marking contact of relay 35, winding of relay 13, tongue B and marking contact of relay 35 to ground. Relay 13 operates at this time, preparing a locking circuit through the winding of relay 15 which is utilized immediately afterward, when brush 12 leaves the A segment and removes the short-circuit from the winding of relay 15.

During the time the brush is travelling from the A segment to the C segment the incoming signal will change from a dot to a dash. The current through the winding of relays 34, and the upper and middle windings of relay 26 will be reversed. The tongue of relay 34 will move to its spacing contact; but due to the effect of its upper winding the tongue of relay 26 will remain on the marking contact and relay 35 will continue energized. The brush next passes over segment C which causes battery to be supplied to the winding of relay 33 which momentarily operates. Since none of the relays which lock up through the contacts of relay 33 has been energized, the relay bank 27-29 and 31 is not effected. Next, the brush passes over a B segment. Since relay 15 is now operated a circuit will be completed from battery 40, armature A and co-operating contact of relay 21, tongue C and marking contact of relay 21, tongue C and marking contact of relay 35, tongue and spacing contact of relay 34, tongue C and marking contact of relay 15, tongue C and spacing contact of relay 17, and the right-hand winding of relay 27 to ground. Parallel circuits are also completed through tongue C of relay 19 to

the right-hand winding of relay 28, and from the spacing contact of relay 34 directly to the right-hand winding of relay 29. Relays 27, 28 and 29, will, therefore, lock up through 5 their respective tongues A and co-operating contacts to effect the filling in of certain impulses to the printer selector magnets, as will be explained later.

The brush now passes over the A segment and relays 16 and 17 are operated and locked in the operated position. During the time the brush is passing from the A to the succeeding C segment the letter space or zero signal will be received, and the armatures of 10 relays 9 and 10 will be operated to the positions shown in the drawings. Due to this positioning of the relay tongues, the current flow through the windings of relays 26 and 34 is such that the tongues of both relays 15 move to their spacing contacts. When relay 35 is de-energized, due to the de-energization of relay 26, relays 13 and 15 will unlock and return to their normal positions, and the 20 breaking away of tongue A of relay 13 from its contact will, in turn, unlock all other relays of the bank 16-20. When the tongue of relay 26 touches the spacing contact, a circuit is established from positive battery 25 46 to respective B tongues of relays 27, 28 and 29, the co-operating contacts of which are connected respectively to printer selector magnets 3, 4 and 5. Current will, therefore, 30 flow from battery 46 to the third, fourth and fifth printer selector magnets which will be 35 operated. Magnets which have now been operated are 1, 3, 4 and 5, which combination corresponds to the printer code combination for the letter A. It will be noted that magnet 1 was operated directly from the received 40 signals, while magnets 3, 4 and 5 were operated from relays 27, 28 and 29. A sixth pulse or printer actuating magnet has not yet been operated. When the brush passes over the C segment relay 33 will be momentarily energized and 45 relays 27, 28 and 29 will be unlocked and restored to normal. The brush now passes over the B segment and a circuit is completed from positive battery to tongue A and co-operating contact of relay 21, tongue 50 C and spacing contact of relay 35, tongue D and spacing contact of relay 15 to magnet 6 and ground. Magnet 6 now operates and, due to the selection set up, the letter A is printed.

55 The brush 12 now passes over A segment and this will operate relays 13 and 15 of the counting bank. During the time a brush is passing over the space between the A and C segments, the dash of the letter N will be received and dash relay 10 will operate.

When relay 10 operates it causes current to flow through the upper and middle windings of relay 26 in opposite directions, the current in the upper winding being in a direction tending to mark the relay and that

in the middle winding tending to space the relay. The effect of the current in the upper winding aided by the current in the lower or biasing winding causes the relay tongue to move to its marking contact. Current flow through the winding of relay 34 is in such a direction as to cause the tongue of that relay to remain on its spacing contact. Operation of relay 26 will, in turn, cause relay 35 to 70 operate and when the tongue of relay 35 leaves its spacing contact the operated relay of the pair, 13 and 14, will be unlocked and restored to normal. When the brush passes over the C segment relay 33 will be operated and remove the locking current from the relays associated with its contact. When the brush passes over the B segment a circuit will be completed through tongue A and corresponding contact of relay 21, tongue C 75 and marking contact of relay 35, tongue and spacing contact of relay 34, to the operating winding of relay 29 which will operate and lock in its operated position. The locking circuit for relay 29 is from battery 45 through 80 the winding, tongue A and corresponding contact of relay 29 to ground.

When the brush passes over the A segment counting relays 13 and 15 will operate and lock. During the time the brush is passing 95 from the A to the C segment the incoming signal will change from a dash to a dot, and relay 9 will operate, causing the tongue of relay 34 to move to its marking contact and maintaining the tongue of relay 26 on its marking contact. Relay 35 is, in turn, maintained operated due to the position of the tongue of relay 26.

The brush will next pass over the C segment which will momentarily operate relay 105 33 and cause relay 29 to unlock. The brush now passes over the B segment and a circuit is completed from the B segment through the tongue A and contact of relay 21, tongue C and marking contact of relay 35, tongue and marking contact of relay 34, tongue B and marking contact of operated relay 15, tongue B and spacing contact of unoperated relay 17, to printer magnet 2 which will now 110 operate.

The brush 12 then passes over a segment A and relays 16 and 17 operate and lock. During the time the brush is passing from the A to the C segment the incoming signal is changed to zero and relays 9, 10, 34, 26 and 35 will all restore to normal. When relay 35 restores, tongue B leaves its marking contact. This unlocks relays 13 and 15. Release of relay 13 in turn releases the other relays in the counting bank. The restoration to normal of relay 26 completes a circuit from battery 46 through the tongue and spacing contact of relay 26 to tongues B of relays 27, 28 and 29, but since none of these is operated this circuit is without effect. Sele- 125

tor magnets 3, 4 and 5 are, therefore, not operated.

The brush now passes over the C segment which momentarily energizes relay 33, but 5 without effect since none of the relays which lock through its contact has been operated. The brush then passes over the B segment which completes a circuit from battery 40 through tongue A and contact of relay 21, 10 tongue C and spacing contact of relay 35, tongue D and spacing contact of relay 15, to printer actuating magnet 6 which initiates the printing of the letter N, the combination for which is the second pulse alone. Other 15 letter combinations can be traced through the circuit in a similar manner.

In addition to selecting and printing any letter which may be desired, it is necessary that figures, punctuation marks, and special 20 characters be received. In order to accomplish this the printer is equipped with type bars having two sets of type, either of which may be used in printing depending upon the position of the printing platen at the time 25 when the type bar is operated.

Having shown how letters are printed the method of actuating the apparatus to print figures will now be described. Assume that the figure 22 is to be received. In order to 30 save line time the figure will be sent as a long figure 2 followed by a short figure 2. The signal for long figure 2 is seen by reference to Fig. 1 to be dot, dot, dash, dash, dash, 35 zero, while that for short figure 2 is as was explained previously the same as that for letter U which is dot, dot, dash, zero.

The first dot received will cause operation 40 of relays 9 and 10 and also of relays 34, 26 and 35. When the brush 12 passes over segment C relay 33 will operate removing locking battery 45 from the locking windings 27, 28, 29, 31 and 32. The brush next passes over the B segment completing a circuit, previously 45 described, to tongue C of relay 35 and thence over its marking contact, tongue and marking contact of relay 34, tongue and marking contact of relay 15, now unoperated, to printer first pulse magnet, 1, which 50 operates. The brush passes over segment A and causes relays 13 and 15 to operate in a manner already described.

The second impulse, also a dot, is received 55 while the brush is between the A segment and the next C segment. When the brush reaches the C segment locking battery 45 is again momentarily removed from the group of relays without effect. When the brush passes over the B segment a circuit is completed 60 from tongue C of relay 35, through tongue and marking contact of relay 34 tongue B and marking contact of relay 15 and thence through tongue B and spacing contact of unoperated relay 17 to printer selector magnet 65 net 2.

The next or third impulse is a dash. This is received while the brush is between segments C and A; it causes the tongue of relay 34 to move to its spacing contact. When the brush reaches segment C relay 33 is energized and operates to unlock certain relays, without effect since none was operated. The brush now passes over a B segment and a circuit is completed from tongue C of relay 35 over the associated spacing contact and the tongue and spacing contact of relay 34 to relay 29 and also over a parallel path comprising tongue C and marking contact of relay 15 and tongue C of unoperated relay 19 to relay 27. Relays 27 and 29 operate and lock to battery 45. The brush passes over the A segment causing the operation of relays 18 and 19. 70 75 80

While the brush is between the C and A segments the fourth pulse, also a dash, is received. When the brush reaches the C segment battery is removed from the locking contacts of relays 27 and 29 which de-energize. When the brush reaches segment B, 85 relay 29 is operated in exactly the same manner as on the fourth pulse but relay 27 is now not operated due to breaking of its circuit at contact C of relay 19 when that relay operated. The A segment is now traversed 90 by the brush causing relay 20 to operate. 95

The fifth pulse, also a dash is now received. When the brush passes over segment C relay 29 is released. When the B segment is traversed relay 29 is again operated and locked in exactly the same manner as on the fourth pulse. At the same time a parallel circuit is completed from tongue C of relay 35 through its marking contact, tongue C and marking contact of relay 20 and winding of relay 32 to ground. Since tongue C of relay 35 is supplied at the instant, with battery from segment B, relay 32 operates. This relay locks to battery 45; in parallel with the locking circuit there is established a circuit from battery 45 through contact and tongue A of relay 32 to printer shift magnet 7. This magnet now operates shifting the printing platen to the upper case position. The brush now traverses the A segment but without effect since all the counting relays are operated. 100 105 110 115

The zero impulse of the signal is now received, causing the tongues of relays 26, 34 and 35 to move to their spacing contacts. When the tongue of relay 26 reaches its spacing contact a circuit is completed from battery 46 over tongue B and associated contact of relay 29 to printer fifth pulse magnet 5. When relay 35 de-energizes and tongue B leaves its marking contacts, relay 13 is de-energized and thereupon all relays of the counting group have locking battery cut off and restore to normal. When the brush reaches the C segment, relays 29 and 32 restore to normal and printer shift magnet 7 120 125 130

de-energizes. Since, however, the printer platen is arranged to mechanically lock in upper case position, this is without effect. When the brush reaches the B segment a circuit is completed from tongue C of relay 35 through the associated contact and tongue C and marking contact of now normal relay 15 to printer actuating magnet 6 initiating operation of the printer. Since the combination selected in the printer was 1, 2, and 5, and since the printing platen is in upper case position, the character printed will be figure 2. It is to be noted in connection with this that although the cable signal was dot, dot, dash, dash, dash, the circuits are so arranged that the fifth impulse sent to the printer is reversed from that of the cable code. In general the printer is so arranged that when a signal comprising five or more dots and/or dashes is received over the cable, the fifth pulse is reversed, thus forming a different printer combination for the printer when a signal is received over the cable; which without the turnover mentioned 25 would be the same as a signal formed by filling in pulses in the manner described for letters A and N.

The brush 12 now passes over an A segment which causes relays 14 and 15 to operate since at this time the zero signal is still being received. This explains why relays 13 and 14 are provided to operate in parallel, namely, so that whether a signal received when all counting relays are unoperated is dot, dash or zero, the counting will be initiated.

During the time that the brush is passing from the A to the succeeding C segment the signal changes from zero to dot. The dot signal is the first signal of the combination for U which is the abbreviation for figure 2, or short figure 2. Relays 34, 26 and 35 now mark. When the B segment is reached by the brush printer magnet 1 operates. Then as the brush passes over the A segment, relays 16 and 17 operate.

Now the second impulse, a dot, is received and relays 34, 26 and 35 remain in the marking position. The brush reaches the C segment and unlocks relays 27-31. When the brush passes over the B segment, printer second pulse magnet 2 is operated. The brush then passes over the A segment causing relays 18 and 19 to operate.

While the brush is passing from C segment to A segment the received signal changes to a dash, the third impulse for letter U in the cable code being a dash. Relay 26 now spaces. When brush 12 reaches the C segment relays 27-31 are again unlocked, ineffectively since they have not been operated. When the brush reaches the B segment relays 28 and 29 are operated. When the A segment is reached relay 20 operates.

During the time the brush traverses the distance from A segment to C segment, the zero

pulse of the U signal is received. The tongues of relays 26, 34 and 35 return to their spacing contacts. A circuit is completed from battery over tongue and spacing contact of relay 26 and tongues B and marking contacts of relays 28 and 29 to operate printer selector fourth and fifth pulse magnets 4 and 5. Also tongue B of relay 35 leaves its spacing contact and de-energizes the locking winding of relay 14 which restores to normal and de-energizes all other counting relays.

Brush 12 now reaches the C segment de-energizing relays 28 and 29 due to removal of locking battery from their windings at the contact of relay 33. The B segment is now reached by the brush and a circuit completed to operate the printer actuating magnet 6. Operation of the printer is now initiated, the combination for the letter U having been selected. Since, however, the printing platen is now in upper case position, operation of the U-2 type bar causes printing of the figure 2.

From the foregoing description of the printing of numeral 22, it is seen that the U-2 type bar is actuated upon reception by the printer of either of two signals, namely, one comprising pulses 1, 2 and 5 and one comprising pulses 1, 2, 4 and 5. This is made possible by a mechanical arrangement of the printer code bars one of them having two notches rather than the single one ordinarily used in standard printers. This feature is well understood and will not be explained in detail. It permits of the selection of the same type bar by two signals differing only in the character of one impulse and permits using a smaller number of type bars. Some other type bars are similarly arranged as will appear hereinafter.

The printer platen will remain in the upper case after being shifted thereto until either of two signals, namely, the word space signal or the unshift signal, is received. This permits the abbreviations for figures, or short figures, as they are commonly called, to be transmitted and the associated figures printed directly as described.

A word space signal consists of three spacing or zero units in the cable code. One of these zero units properly belongs to the last letter received and two additional zero units are sent when a word space is desired. When the three zero units are received it is necessary that the printer space without printing. In order to show how the printed platen is restored to its normal position and at the same time describe the word space operation, we will consider the condition of the printer after the platen has been shifted to the upper case position and a portion of the combination for the letter A which in this upper case position would cause the figure 1 to be printed, received.

Assuming now that the combination for the letter A as shown in Fig. 2 and as described previously, has been partially received, and that the dash of that combination has just been completed and the dot and dash relays 9 and 10 restored to normal, we find that, next, the brush will pass from the C segment to the A segment. All the relays of the counting bank will be in their unoperated positions. When the brush passes over the C segment, relay 33 will be momentarily operated and will unlock relay 32, thus de-energizing shift magnet 7. (It is to be understood that the de-energization of shift magnet 7 does not cause the printer platen to return to its lower case position, since the arrangement to return the platen is a well known mechanical one operative when the word space type bar has been actuated.) Now, when the brush passes over the B segment, a circuit will be completed through tongue A and contact of relay 21, tongue C and spacing contact of relay 35, tongue D and spacing contact of relay 15, to operate the start magnet 6 which will initiate the printing of the figure 1, previously selected. Brush 12 now passes over the A segment and causes energization of relays 13 and 15, which lock in their operated positions. When the brush passes over the next C segment relay 33 is again momentarily energized, but without effect. When the brush passes over the B segment a circuit is completed from battery to tongue A of relay 21 and co-operating contact, tongue C and spacing contact of relay 35, tongue D and marking contact of relay 15, and the right-hand winding of relay 31. Relay 31 now operates and locks through its tongue A and co-operating contact. The operation of relay 31 causes a completion of circuits from battery over tongues D, E and F to magnets 1, 3 and 5 of the printer, which are energized, tripping the printer code bars in a well known manner.

The brush now passes over segment A, causing counting relays 16 and 17 to be energized. Then the brush passes over the B segment, completing a circuit from the B segment through tongue A and contact of relay 21, tongue C and spacing contact of relay 35, tongue D and marking contact of relay 15, tongue D and marking contact of relay 17, tongue D and spacing contact of relay 19, to operate the actuating magnet 6 which will initiate the operation of the printer. Since selecting magnets 1, 3 and 5 have been operated, the type bar corresponding to the word space will be operated. Since this type bar is not provided with type, no character will be printed but the platen will be spaced in a manner common in the printer art. Since the word space type bar is arranged to operate the unshift mechanism of the printer, the platen is now returned to the lower case

position. Should it be desired to unshift without spacing, this may be accomplished by sending the unshift signal shown on Fig. 1, which operates the unshift mechanism directly without affecting the printer spacing mechanism.

It will be observed that during the operation of the circuits upon reception of the word space signal relay 31 was operated and locked during a portion of the time. This operation was effective to operate printer selector magnets 1, 3 and 5 for operating the word space type bar. Relay 31 has an additional use which is the energization of other printer selector magnets in the event that there are only two spacing or zero units received over the cable. If a dot or dash had been received after only two units of zero or no current signals, relay 31 would have been energized at the time such dot or dash was received. In this event a circuit would be completed from battery 46 through the tongue and marking contact of relay 26, tongues B and C of relay 31 and respective contacts, printer selector magnets 2 and 4 to ground. Since magnets 1, 3 and 5 had already been operated, the character selected would then be that the combination for which is all five impulses, which is seen by reference to Figure 1 to be the asterisk. The asterisk is used as an indication of incoming signal failure.

The printer combination for the letter T, as shown in Fig. 1 requires that only the fifth selector magnet be operated. Referring now to Fig. 2, it will be noticed that when relay 15 is unoperated, the operating circuits of relays 27 and 28 are open at tongue C of relay 15 and therefore a single unit dash cable signal will have only the fifth impulse filled in instead of filling in impulses 2, 3 and 4 in addition. The letter T is the only one in which an impulse is filled in in this manner. After the fifth selector magnet has operated, the sixth pulse magnet is operated, in the same manner as for the other selection, and the letter T printed.

In order to reduce the number of type bars in the printer it is possible to have some type bars operated on two different combinations, when those combinations differ only by the character of one impulse. For example, the selecting combination in the printer code for the letter U operates the first, second, fourth and fifth printer selector magnets, while the printer combination for the figure 2 operates the first, second and fifth printer selector magnets, thus differing only by the character of the fourth impulse of the combination. By suitably arranging the notches on the printer code bars, it is possible to have the same type bar operated when either of two combinations is received on the printer magnets. The letter U having less than five dots or dashes in its cable combination will print

in the lower case. Therefore, the letter U will actually be printed; while if the cable signal for the figure 2 is received, the printer platen will be shifted into the upper case, and, therefore, a figure 2 will be printed. The letter N and figure 2 also differ by only one impulse in their printer combinations, and have been arranged in the same manner, as have been the hyphen and the letter X.

10 The foregoing material is given by way of description only, and is in no way to limit the scope of the appended claims.

What is claimed is:

15 1. In a telegraph system, the combination of means for receiving cable code signals, means for automatically printing characters corresponding to said signals, means for rendering said printing means inoperative, and means operative on receipt of signals 20 having a predetermined characteristic to restore said printing means to operative condition.

25 2. In a telegraph system, the combination of means for receiving signals of unequal length, normally operative means for printing characters corresponding to said signals, means for rendering said printing means inoperative, and means for restoring said printing means to operative condition upon receipt 30 of a signal exceeding a predetermined length.

35 3. In a telegraph system for receiving signal combinations of unequal length, a printer operable only by signal combinations of equal length, relay means responsive to said received signal combinations for converting them to signal combinations of equal length, normally operative means to effect operation of said printer in accordance with said converted signal combinations and means to 40 render said last mentioned means inoperative.

45 4. In a telegraph system for receiving signal combinations of unequal length, a printer operable only by signal combinations of equal length, relay means responsive to said received signal combinations for converting them to signal combinations of equal length, means normally operative to effect operation of said printer in accordance with 50 said converted signal combinations, means to render said last mentioned means inoperative, and means to restore said last mentioned means to operative condition when said received signal combinations exceed a certain 55 length.

60 5. In a telegraph system, the combination of means for receiving signal combinations comprised of unequal numbers of different polarity impulses, counting means progressively operative in accordance with the number of impulses in each received signal combination, means for printing characters in accordance with the received signal combination, means for rendering said printing means inoperative, and means for restoring 65

said printing means to operative condition when all said counting means are operated.

6. In a telegraph system, the combination of means for receiving signal combinations comprised of different numbers of impulses, counting relays operable in accordance with the number of impulses in a received signal combination, printing means operable in accordance with the received signals, means to render said printing means inoperative and a relay operable when all said counting relays have been operated to restore said printing means to operative condition.

7. In a telegraph system, in combination, means for receiving signal combinations of unequal length, means progressively operable in accordance with the length of said signal combinations, a relay operable by said last mentioned means, printing means normally operable in accordance with said signal combinations and under control of said relay, a key for de-energizing said relay to render said printing means inoperative, said relay being re-energized when a signal combination exceeding a certain length is received.

8. In a telegraph system, the combination of means for receiving signal combinations comprising unequal numbers of impulses of different polarity, and means for reversing the polarity of the last polar impulse of a signal combination when the impulses therein exceed a predetermined number.

9. In a telegraph system, the combination of means for receiving signal combinations comprising unequal numbers of impulses of different polarity, means for reversing the polarity of the last polar impulse of a signal combination when the impulses therein exceed a predetermined number, and means operable in accordance with the converted signal combination to print the character corresponding to the received signal combination.

10. In a telegraph system, the combination of means for receiving signal combinations comprising unequal numbers of impulses of different polarity, means for altering the polarity of the last polar impulse of a signal when the impulses therein exceed a predetermined number, printing means operable in accordance with said converted signal combinations and shiftable to upper and lower case positions, and means to shift said printing means to the upper case position on receipt of a signal combination of impulses exceeding the predetermined number.

11. In a telegraph system, the combination with means for receiving signal combinations comprising unequal numbers of impulses of different polarity, of printing means comprising type bars having upper and lower case characters, means for reversing the polarity of the last polar impulse of a signal when the impulses therein exceed a predetermined total, and means for selecting a type bar and character thereon in ac-

cordance with the converted signal combination.

12. In a telegraph system utilizing a code combination representing a character and an abbreviation therefor, a printing device having a type bar carrying both the character and the abbreviation, means for selecting said type bar in accordance with said code, and means to determine whether said character or said abbreviation shall be printed.

13. In a telegraph system, means for receiving cable code signal combinations of different numbers of impulses, polar relays controlled by said receiving means, a distributor co-operating with said polar relays to control recording means comprising a telegraph printer having a selecting mechanism operable by signal combinations of equal numbers of impulses.

20 14. In a telegraph system wherein cable code signals composed of dot, dash and zero elements are received, intermediate polarized means for relaying said elements, a distributor and relay means co-operating with 25 said polarized means, said distributor and relay means being arranged to control a telegraph printer having a selecting mechanism adapted to be controlled by uniform length signals formed of marking and spacing impulses.

In witness whereof, I hereunto subscribe my name this 23rd day of December, 1931.

ALDER F. CONNERY.
